UNITED STATES PATENT OFFICE.

MAGNUS SCHIMMEL, OF ST. LOUIS, MISSOURI.

DESIGN FOR A RING.

SPECIFICATION forming part of Design No. 35,795, dated March 11, 1902.

Application filed February 17, 1902. Serial No. 94,571. Term of patent 7 years.

To all whom it may concern:

Be it known that I, MAGNUS SCHIMMEL, a citizen of the United States, residing at St. Louis, State of Missouri, have invented and produced a new and original Design for Rings, of which the following is a specification, reference being had to the accompanying drawings, forming a part hereof.

Figure 1 is a front elevation of the ring. Fig. 2 is a side elevation thereof. Fig. 3 is a rear view thereof, and Fig. 4 is a perspective.

As shown in the drawings, the leading or material feature of my design consists of a central front lobe 1 and two side lobes 2, as shown, the lobe 1 having centrally disposed at one end thereof in raised outline a cross C, followed by a large bead B, the latter being followed by three small beads b, at the end of which is a terminal large bead B. Disposed along the edge of the lobe 1 on each side of the longitudinal axis thereof are ten small beads b. Along the edge of each lobe

2 are two large beads B, separated, respectively, by five small beads b on one side and ten small beads b on the other, the whole conforming to the arrangement and disposition of the strung beads of a rosary. The series of lobes are circumscribed by a marginal raised edge E. The narrow back portion or band 3 of the ring has formed therein ten 30 raised roses R, distributed equal distances apart, said narrow band being provided with a raised marginal edge E'.

Having described my invention, what I claim as new, and desire to secure by Letters 35 Patent, is—

The design for a ring, as herein shown and described.

In testimony whereof I affix my signature in presence of two witnesses.

MAGNUS SCHIMMEL.
